Primary Examiner — Cary M Robinson*Assistant Examiner* — Emily Anna Saunders(74) Attorney, Agent, or Firm — PATENTFILE, LLC;
Bradley C. Fach; Steven R. Kick(57) CLAIM

The ornamental design for a card deck box, as shown and described.

DESCRIPTION

FIG. 1 is a top, rear perspective view of the card deck box, of the present invention;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings show portions of the card deck box that form no part of the claimed design.
